MAINE, A CORPORATION OF MAINE.

METHOD AND APPARATUS FOR ELIMINATING UNDESIRED VIBRATIONS.

1,319,521.

Specification of Letters Patent.

Patented Oct. 21, 1919.

Application filed June 8, 1917. Serial No. 173,614.

To all whom it may concern:

Be it known that we, REGINALD A. FESSENDEN, of Brookline, in the county of Norfolk and State of Massachusetts, and FREELAND H. LESLIE, of Milton, in said county and State, citizens of the United States, have invented a new and useful Improvement in Methods and Apparatus for Eliminating Undesired Vibrations, of which the following is a specification.

Our invention relates to vibratory bodies, and more especially to sound-producing bodies, and still more especially to bodies vibrating at their natural frequencies, such as diaphragms, tuning forks, rods and the like.

It has for its object the suppression to any desired extent of such vibration frequencies as are not desired, thereby broadly increasing the efficiency of the generation and utilization of vibratory motion.

In the accompanying drawings, forming a part of this specification, Figures 1 and 2 are diagrams illustrative of the theory of our method, and

Figs. 3 and 4 show diagrammatically forms of apparatus for carrying out our invention.

It is well known in the art that vibratory bodies tend to vibrate at certain definite frequencies, which are called their natural periods.

For example, a telephone diaphragm tends to vibrate at a period in the neighborhood of 1000 and a submarine oscillator diaphragm, of the type shown in United States Letters Patent No. 1,167,366 granted to said Fessenden January 4, 1916, as at present constructed, tends to vibrate at frequencies of 540 and 1100, approximately.

The presence of these natural vibrations is frequently very objectionable. For example, in the telephone they unduly strengthen the higher tones of the voice though still permitting speech.

In the submarine oscillator they are so strong, however, that they do not transmit articulate speech at all. When diaphragms are used for engine indicators, as by Perry's method, the natural period of the diaphragm tends to give incorrect indicator cards. Where a diaphragm is used to analyze sounds the overtones of the diaphragm make the research one of great difficulty, as

may be seen from Miller's "Science of Musical Sounds," lecture 5. Similar remarks apply to the notes of the diaphragm on phonograph records.

The applicants have discovered a method by which these undesirable harmonics may be eliminated, or reduced to any desired degree. The theory is illustrated in Fig. 1, where 19 is the axis of the ordinates; 11, 12, 13, 14, 15 is the curve showing the relation between the intensity of sound and frequency of the submarine oscillator, intensities being ordinates and frequencies abscissæ, the axis being at the left.

It will be noticed that there are two marked points of resonance, one at 12 which has a frequency of about 500, and the other at 14 which has a frequency of about 1100.

16 and 17 are figures in the form of humps similarly so drawn that if 16 be subtracted from the resonance hump 12 and 17 be subtracted from the resonance hump 14 the remaining intensity will be uniform for all frequencies, as shown in Fig. 2, where the strip 18 shows the intensity left after subtracting the figures 16 and 17 from the original curve.

The applicants have discovered that these figures 16 and 17 correspond approximately to the absorption humps of electrical resonant circuits and that by properly proportioning the self-induction, resistance and capacity in such a circuit, the amount of sound absorbed can be made to correspond quite closely with any desired figure, as for example, 16 or 17, and the diaphragm thus made to vibrate substantially correctly over the entire range of frequencies. Fig. 3 shows such an arrangement as actually used for submarine telephony, which the applicants have accomplished up to a distance of five miles with clear and sharp articulation, whereas before only indistinct sounds could be observed, and thus for the first time it is possible for human beings to talk to one another from one submarine to another through the water there being two absorption circuits 23, 24 and 25 producing the absorption hump 16 and also 26, 27 and 28 producing the absorption hump 17.

In Fig. 3, 21 is a telephone transmitter, here shown of the ordinary type with battery 40, though any of the well known amplifying devices known in the art may be

used with it where more power is desired. 29 and 30 are wires leading from the transmitter to the oscillator 22.

On whistling into the transmitter 21 at 5 different frequencies, commencing with a frequency of about 200 and gradually increasing to a frequency of about 1500, a curve of a character such as is shown at 11, 12, 13, 14, 15 in Fig. 1 will be obtained on 10 plotting the resulting intensities. If the transmitter 21 be spoken into, with this strongly resonant type of diaphragm attached to the oscillator, only inarticulate sounds will be heard. If, however, two 15 shunted circuits are placed across the leads 29, 30, for example the circuit containing the inductance 23, resistance 24 and capacity 25, and also the circuit containing the inductance 26, resistance 27 and capacity 28, these 20 self inductances, resistances and capacities being suitably proportioned, the distortion may be entirely cured, and on now whistling into the transmitter 21 at different frequencies, a substantially even curve, as shown in 25 Fig. 2, will be obtained for the relation between frequency and intensity.

On talking into the transmitter 21 speech will now be emitted by the oscillator 22 very clearly and very distinctly.

30 We have taken as an illustration a diaphragm having its oscillator strongly resonant at two points, owing to its construction, but the same general system may be applied whether the number of resonant 35 points be one or ten.

In Fig. 4 is shown this invention applied to a vibrating shaft.

31 is the pedestal; 32 the shaft; 33, 34, 35 are bearings; 39, 38 are piston rods running on eccentrics 36, 37 placed on the shaft as shown. 44 and 45 are cylinders open at the lower end; 40, 41 are pistons attached to the piston rods 39, 38; and 43, 42 are holes in the piston for permitting air to 45 escape into and out of the cylinders 44 and 45 as the pistons 40 and 41 move up and down.

The applicants have found that the part 50 of the shaft between the bearing 34, 35 may be considered, for mathematical purposes, as an electric circuit; the mass of the shaft corresponding to electric inertia, that is, self induction, the elasticity of the shaft corresponding to the reciprocal of electrical 55 elasticity, that is, capacity, and the friction of the shaft corresponding to the ohmic resistance.

Similarly, the portion of the shaft between the bearing 33, 34 may be mathematically 60 considered as another electric circuit.

And these two mathematically-considered electric circuits may be considered as coupled together electrically, the extent depending upon the rigidity of the bearing 34.

65 For example, if the bearing 34 fits so

tightly that a vibration made by bending and suddenly releasing the shaft between the bearings 34, 35 is transmitted in a very slight degree to the portion of the shaft between the bearings 33, 34, then the coupling is considered to be what is known electrically as a loose coupling and the extent of the tightness of the coupling may be determined by measuring the extent to which the vibration of definite amount 70 passes from the portion of the shaft between the bearings 34, 35 to the portion between the bearings 33, 34.

From this data a set of equations may be written down, similar to the well known 80 equations for electrically-coupled circuits, and from them the various modes of vibrations of the shaft at different frequencies, the different resonance points and the amount of resonance may be calculated. 85

Having thus, or experimentally, determined the amount of resonance at different frequencies, if it is desired to eliminate that resonance, the size of the cylinders 44, 45 and the stroke of the eccentrics 90 36, 37, and the size of the air-throttling passages 43, 42 and the mass of the pistons and piston rods 40, 39, 41, 38 are so determined that, just as in Fig. 1, the amount of power absorbed by the throttling of the 95 air through the air pistons 43, 42 is just sufficient to absorb the undesired resonant energy so that the shaft runs without any strongly marked resonant frequency.

In the electrical case shown in Fig. 3, the 100 applicants have found that the inductance for the 540 period should be about 7 millihenries and for the 1200 frequency about 2 millihenries, and that the capacity for the 540 period should be about 10 microfarads and the capacity for the 1200 period about 2 microfarads, the resistance in each case being approximately 1 ohm. 105

It is well known to those skilled in the art that in place of using absorbing circuits 110 placed in shunt across the electric circuit, other equivalent means may be used.

What we claim is:—

1. The method of eliminating undesired vibrations from a vibrating element, which 115 consists in operatively connecting to the vibrating element a second vibratory energy-absorbing element, adjusting the frequency-determining constants of said second vibratory element so that the frequency 120 of said second vibratory element is substantially the same as the frequency of the undesired vibrations of the first vibrating element which it is desired to eliminate, and adjusting the frictional energy-absorbing 125 constant of said second vibratory element so that the difference between the energy absorbed for a given frequency by the second vibratory element and the energy generated for said frequency by the first vi- 130

brating element will be equal in amount to the amount of vibration desired at said frequency.

2. The method of eliminating undesired vibrations from a vibrating element, which consists in operatively connecting to the vibrating element a second vibratory energy-absorbing element, adjusting the frequency-determining constants of said second vibratory element so that the frequency of said second vibratory element is substantially the same as the frequency of the undesired vibrations of the first vibrat-

ing element which it is desired to eliminate, and adjusting the frictional energy-absorbing constant of said second vibratory element so that the difference between the energy absorbed for a given frequency by the second vibratory element and the energy generated for said frequency by the first 20 vibrating element will be substantially equal in amount for all frequencies in the neighborhood of the undesired frequency.

REGINALD A. FESSENDEN.
FREELAND H. LESLIE.
